UNITED STATES PATENT OFFICE.

HARVEY S. PARDEE AND RALPH FLETCHER SEYMOUR, OF RAVINIA, ILLINOIS; SAID
SEYMOUR ASSIGNOR TO SAID PARDEE.

DESIGN FOR A RADIATOR CAP.

Application filed January 30, 1925. Serial No. 12,205. Term of patent 14 years.

To all whom it may concern:

Be it known that we, HARVEY S. PARDEE and RALPH FLETCHER SEYMOUR, both citizens of the United States, and both residents of Ravinia, Lake County, State of Illinois, have invented a new, original, and ornamental Design for Radiator Cap, of which the following is a specification, reference being had to the accompanying drawing, forming part hereof, in which Fig. 1 is a front elevation, and Fig. 2 is a side elevation.

We claim:

The ornamental design for a radiator cap, substantially as shown.

In testimony whereof, we have signed our names to this specification this 26th day of January, 1925.

HARVEY S. PARDEE.
RALPH FLETCHER SEYMOUR.
